UNITED STATES PATENT OFFICE.

ROBERT O. KING, OF BUFFALO, NEW YORK.

BUILDING.

1,056,103.

Specification of Letters Patent. Patented Mar. 18, 1913.

Application filed July 22, 1911. Serial No. 639,886.

To all whom it may concern:

Be it known that I, ROBERT O. KING, a citizen of Canada, residing at Buffalo, in the county of Erie and State of New York, have invented new and useful Improvements 5 in Buildings, of which the following is a specification.

This invention relates to a building construction and more particularly to means for 10 connecting the roof bars and glass with the side bars and glass of green houses.

It is the object of this invention to provide a connection for this purpose which will effectively unite the roof and side bars 15 and also the roof glass and side glass so as to form a tight, strong and durable construction which can be produced at comparatively low cost and which will also effectually prevent the formation of icicles on the 20 outer side of the eave and offer a minimum obstruction to the entrance of light into the green house.

In the accompanying drawings consisting of 2 sheets: Figure 1 is a fragmentary side 25 elevation of a green house embodying my improvements. Fig. 2 is a top plan view thereof. Fig. 3 is a fragmentary vertical section in line 3—3, Fig. 4. Figs. 4, 5 and 6 are fragmentary vertical transverse sections 30 in the correspondingly numbered lines in Fig. 1. Figs. 7 and 8 are fragmentary sections in lines 7—7 and 8—8, Fig. 4, respectively. Figs. 9 and 10 are fragmentary perspective views of one of the roof bars and 35 one of the side bars. Fig. 11 is a perspective view of one of the joint brackets. Figs. 12 and 13 are fragmentary perspective views of two eave bars on opposite sides of the joint bracket. Fig. 14 is a perspective view of 40 one of the supporting brackets forming part of the corner fixture for connecting the opposing ends of a side post and a rafter with the opposing ends of a roof bar and side bar.

45 Similar characters of reference indicate corresponding parts throughout the several views.

1 represents a plurality of upright or side sash bars which are spaced at suitable distances apart and form part of the side wall of the green house or other building structure and 2 represents a plurality of inclined roof sash bars each of which engages at its outer or lower ends with the upper end of 55 one of the side bars by means of a bevel joint.

3 represents the panes of the roof glass each of which rests at its opposite transverse edges on upwardly facing ledges or shoulders 4 formed on the opposing sides of 60 an adjacent pair of roof bars and 5 represents the panes of the side glass of the building each of which engages at its opposite vertical edges with outwardly facing shoulders 6 formed on the opposing sides of a 65 pair of adjacent side sash bars. The transverse and vertical edges of the roof and side panes of glass are bedded in putty in the usual manner so as to render the joint between the same and the roof and side bars 70 water tight.

7 represents a plurality of eave bars each of which is preferably constructed of sheet metal and extends lengthwise from one pair of roof and side bars to another pair of roof 75 and side bars at the joints between these two pairs. This eave bar is of angular form in cross section so as to provide an upper flange 8 which projects inwardly underneath the lower edge of the lowermost pane 80 of glass of the roof and rests on the shoulders 4 of the roof bars while its lower flange 10 projects downwardly and engages with the outer side of the uppermost pane 85 of the side glass on the upper edge thereof. By this means any water running down the roof glass is delivered upon the outer side 90 of the eave bar and conducted by the latter downwardly to the outer side of the side glass.

The glass commonly used in green houses is curved owing to its method of manufacturing and in applying this glass the same is usually placed upon the roof bars so that its crown is arranged parallel with the roof 95 bars and its curvature is upward and in a direction lengthwise of the eave bars. The glass panes of the side wall are in like manner applied to the side bars so that the crown of these panes are arranged parallel with the side bars and the arch or curvature is outward and in a direction lengthwise of the eave bar. For the purpose of producing a tight joint between each eave bar and the adjacent roof glass 105 and side glass the upper flange of each eave bar is curved, bowed or bent upwardly and lengthwise so that it fits snugly against the curved underside of the adjacent lower part of the roof glass and the lower flange of 110 each eave bar is likewise curved, bowed or bent outwardly so as to fit snugly against the

curved outerside of the adjacent side glass at the upper edge thereof. By this means a close joint is formed between the eave bar and the adjacent roof and side glasses which is neat in appearance, which is capable of being produced at low cost and which offers a minimum obstruction to the passage of light into the green house.

Although the drawings represent the upper and lower flanges of the eave bar arranged at the same angle as the roof and side glasses this need not necessarily be so inasmuch as the flanges of the eave bar may be arranged at a slightly different angle from the roof and side glasses and still permit of forming a weather tight joint between the eave bar and the roof and side glasses.

In other forms of eave construction heretofore used in green houses a heavy member of wood or iron or a combination of wood and iron was placed between the roof glass and side glass which construction is open to serious objection inasmuch as it obstructs a large amount of light at all times, and at certain seasons of the year becomes blocked with ice and long icicles which collect on the outer side of the glass and frequently break the glass and also obstruct the light to the green house. In the present construction, the joint between the roof and side glass is made by the use of but a very small iron member which is not combined with any wood. By having the roof glass lap over this eave bar or member and the side glass lap under it and by having the eave bar bent lengthwise to conform to the curve of the glass, a very tight or close fitting joint is obtained between the same without the use of any wood or other flashing as is commonly done. The absence of this flashing permits the heat of the green house to act directly on the comparatively light iron eave bar and heat the same sufficiently to keep it free from ice at all times. Furthermore, on account of the smallness of the eave bar and the simplicity of its construction it obstructs very little light.

Various means may be employed for connecting the roof and side sash bars and the eave bars on opposite sides of the same. The preferred means for this purpose which are shown in the drawings comprise a plurality of joint brackets 11 each of which is constructed in the form of an angular cap which is channel-shaped in cross section. This bracket extends across the outer end or corner of the joint between a pair of roof and side sash bars and embraces these bars adjacent to this joint. The upper inwardly projecting part of this annular bracket is secured to the upper side of the roof bar by means of a screw 12 and the downwardly projecting part of this bracket is secured to the outer side of the adjacent side bar by

means of a screw 13. On its opposite longitudinal sides each joint bracket is provided with a pair of laterally projecting ears, wings or lugs 14 which lap over the adjacent ends of the upper flanges of the eave bars on opposite sides of the respective roof and side bars. Each of these wings or lugs may be secured to one of the eave bars by any suitable means but preferably by the means shown in the drawings which consists of a bolt 15 passing through the respective lug of the joint bracket and the upper flange of the adjacent eave bar. The lugs of the joint bracket are sufficiently long to permit the fastening bolts 15 to clear opposite sides of the side bar and roof bar and thus permit of freely assembling these parts. At their outer ends the lugs of the joint brackets are thickened somewhat as shown at 16, thereby forming stops which are engaged by the lower edges of the lowermost pane of the roof glass and thus prevent the same from sliding off the roof bars and eave bars. The thickening of each lug of the joint bracket is arranged only at the outer end thereof, thereby forming a recess or passageway 17 between the underside of each lug and the upper side of the eave bar adjacent to the body of the bracket through which water may freely flow from the roof glass to the side glass, thereby preventing such water from gathering next to the wooden roof bars and side sash bars at the joint between the same which otherwise would eventually rot the same. In addition to forming a bracket which connects the roof and side bars and supports the eave bars on opposite sides of the same the joint bracket also serves the purpose of covering the joint between the side sash bar and the roof sash bar, thereby preventing water from getting into this joint between these bars and rotting the same.

18 represents one of the purlins whereby the roof and side sash bars are secured in place and spaced apart the proper distance for receiving between them the glass and eave bars. Each of these purlins may be constructed of any suitable form in cross section and of any suitable structural material. It is preferable, however, to construct this purlin of iron and of tubular form or piping, as shown in the drawings. The purlin is arranged at the inner corner between some of the companion pairs of roof and side sash bars by means of clips 19 each of which embraces the inner side of the purlin and may be secured at its opposite ends to the inner sides of the roof and side sash bars by screws, as shown in Fig. 4, or by any other suitable means.

The main frame of the structure preferably comprises an upright post 20 arranged adjacent to the inner side of one of the side sash bars and an inclined rafter 9 ar-

ranged adjacent to the underside of one of the roof sash bars. The adjacent upper end of each post and the lower end of the companion rafter are connected with each other and with the adjacent roof and side sash bars and the purlin by means of a fitting or coupling comprising a head or top 21 secured to the upper end of the post, a foot 22 arranged at the lower end of the rafter, 10 a supporting bracket 23 provided at its outer end with ears or lugs 24 which are secured respectively to the roof and side sash bars by means of screws 25 and provided in its intermediate part with an opening 26 in which the adjacent part of the purlin is supported, and a fastening bolt 27 passing through the inner end of the supporting bracket and through said head and foot. By this means the roof and side wall 20 are reliably supported on the main frame of a building and the roof sash bars and the side sash bars are firmly held in the proper position relatively to each other with a minimum obstruction of light to the interior 25 of the green house.

By locating the purlin at the junction of the roof sash bars and the side sash bars, it is possible to change the angle of the roof and side bars relatively to each other to a 30 considerable extent without changing the construction of the cap or joint bracket 11. The joint brackets 11 also form a flexible metal band between the several eave bars and not only increase the rigidity of the 35 same but also allow ample play for expansion and contraction.

I claim as my invention:

1. A building having a plurality of roof sash bars arranged side by side, a plurality 40 of side sash bars arranged side by side and each roof bar being in line with one of said side sash bars, a plurality of eave bars each of which extends across the space between two adjacent pairs of roof and side bars, 45 brackets secured to said roof and side sash bars and each extending across the joint between the companion roof and side bars and having lugs to which the ends of the eave bars are secured, an upper roof glass lapping 50 over the upper side of the upper part of said eave bar, and a side glass lapping against the inner side of the lower part of said eave.

2. A building having a plurality of roof

sash bars arranged side by side, a plurality 55 of side sash bars arranged side by side and each roof bar being in line with one of said side sash bars, a plurality of eave bars each of which extends across the space between two adjacent pairs of roof and side bars, brackets 60 secured to said roof and side sash bars and each extending across the joint between the companion roof and side bars and having lugs to which the ends of the eave bars are secured, an upper roof glass lapping over 65 the upper side of the upper part of said eave bar, and a side glass lapping against the inner side of the lower part of said eave, each of said lugs being recessed on its underside adjacent to said bracket to form a 70 drain passage.

3. A building comprising a plurality of roof sash bars, a plurality of side sash bars arranged at an angle to the roof sash bars and each engaging at its upper end with one 75 of said roof sash bars, a purlin engaging with said bars at the inner corner of the angle between the roof and side bars, and a clip embracing said purlin and secured at its opposite ends to a companion pair of roof 80 and side bars.

4. A building comprising a plurality of roof sash bars, a plurality of side sash bars arranged at an angle to the roof sash bars and each engaging at its upper end with one 85 of said roof sash bars, a post, a rafter, and a fitting connecting the post, rafter and said roof and side bars.

5. A building comprising a plurality of roof sash bars, a plurality of side sash bars 90 arranged at an angle to the roof sash bars and each engaging at its upper end with one of said roof sash bars, a purlin engaging with said side and roof bars at the inner corner of the angle between them, a post, a 95 rafter, a head on said post, a foot on said rafter, a supporting bracket having an opening which receives said purlin and lugs which are secured to said roof and side bars, and a connection between said head, foot 100 and supporting bracket.

Witness my hand this 19th day of July, 1911.
